GRINDING MACHINE

Bernard P. Appel, Cleveland Heights, and Joseph F. Klukan, Garfield Heights, Ohio, assignors to Chandler Products Corporation, Euclid, Ohio, a corporation of Ohio

Application August 9, 1947, Serial No. 767,788

5 Claims. (Cl. 51—103)

1

This invention relates to improvements in centerless grinding machines for grinding articles of circular cross section.

An object of the invention is to provide a novel and improved centerless grinder, having opposed rotatable grinding and regulating wheels mounted in spaced relationship to form a work receiving throat, with improved means for sequentially feeding workpieces into the throat.

Another object of the invention is to provide a novel and improved centerless grinding machine having opposed grinding and regulating wheels, the machine being so constructed and arranged that the work is axially fed between the grinding and regulating wheels and is thereafter moved into engagement with the grinding wheel and removed therefrom by operation of the regulating wheel without translation of the axis of the latter.

A further object of the invention is to provide a novel and improved centerless grinding machine having opposed rotatable grinding and regulating wheels mounted in spaced relationship to form a work receiving throat therebetween, with the said regulating wheel having a segment of its periphery removed to provide a recessed portion and the remainder of the periphery including an eccentric portion, the work being axially inserted within the throat by an improved feeding means and thereafter moved into engagement with the grinding wheel by the said eccentric portion of the regulating wheel for effecting material removal, the recessed portion of the regulating wheel allowing the work to drop by gravity from its position within the throat after the grinding is completed.

A still further object of the invention is to provide a centerless grinder, having opposed rotatable grinding and regulating wheels mounted in spaced relationship, with improved means for feeding elongated workpieces axially into the space between said wheels in timed relationship with the rotation of said regulating wheel.

The invention further resides in certain novel features of construction, and combinations and arrangements of parts, and further objects and advantages thereof will be apparent to those skilled in the art to which it pertains from the following description of the present preferred embodiment and a modification thereof described with reference to the accompanying drawings, in which similar reference characters represent corresponding parts throughout the several views, and in which:

Fig. 1 is a side elevation of a grinding machine

constructed in accordance with the invention, certain parts being broken away and others shown in section;

Fig. 2 is an end elevation of the grinding machine illustrated in Fig. 1, portions of the machine being broken away to more clearly reveal the construction of the novel feeding mechanism;

Fig. 3 is a fragmentary plan view of the machine illustrated in Fig. 1 with a part of the cover for the regulating wheel removed to show the feed controlling member and other parts of the feeding mechanism;

Fig. 4 is a side elevational view of the present preferred embodiment of the novel feeding mechanism of this invention detached from the grinding machine;

Fig. 5 is a detached perspective view of the feed controlling member of the feeding mechanism illustrated in Fig. 4;

Fig. 6 is a fragmentary elevational view showing the regulating wheel and a portion of the grinding wheel of the machine and their mode of operation;

Fig. 7 is a side elevation view of a novel regulating wheel dressing or truing means mounted upon a grinding machine of the type illustrated in Figs. 1-6 in place of the dressing means shown therein; and

Fig. 8 is a sectional view taken approximately on the line 8—8 of Fig. 7 further illustrating the construction and operation of the novel regulating wheel dressing means, portions being broken away to more clearly show the construction:

The illustrated grinding machine is of conventional design, except as hereinafter described, and is constructed similar to that disclosed in U. S. Patent No. 1,575,558, issued to Einstein et al. on March 2, 1926. Such a machine comprises a main frame or base 10 having a substantially horizontal bed or top plate 11 upon which are supported suitable bearings for rotatably mounting a grinding wheel 12. The bed or top plate 11 is also provided with dovetailed ways 13 upon which a regulating wheel supporting housing 14 is slidably mounted, the base of this housing being provided with dovetail portions 15 cooperating with the ways 13. The forward end of the regulating wheel support or housing 14 is provided with suitable bearings for rotatably mounting a regulating wheel 16 which may be moved towards and away from the grinding wheel 12 by means of a threaded shaft 17, the inner end of which is rotatably secured within the support 14 and held

from longitudinal movement with respect thereto. The threads of the shaft 17 pass through a stationary nut 18 supported by a bracket 19, mounted upon the base of the machine, and the outer end of the threaded shaft 17 is provided with a hand wheel or spider 20 by which the shaft 17 may be rotated.

The grinding wheel 12 is provided with a suitable housing or cover 21 and adjacent the grinding wheel is mounted a conventional truing or dressing device, generally designated 22. Mounted upon the forward portion of the regulating wheel support or housing 14 is a similar conventional truing or dressing device, generally designated 23. These devices 22 and 23 are employed in a conventional and well known manner for dressing or truing the periphery of the grinding wheel 12 and a portion of the periphery of the regulating wheel 16.

As will be apparent from the drawings, and as is well known in the art, the grinding wheel 12 and regulating wheel 16 are both formed of suitable abrasive material, bonded together, and mounted upon arbors in a manner such that the two wheels are in substantial alignment and spaced apart sufficiently to provide a work receiving throat 24 therebetween. The grinding wheel 12 is rotated in a clockwise direction by means of a motor 25 and suitable power transmission mechanism which is of conventional design and hence is not here illustrated. The regulating wheel 16 is likewise driven in a clockwise direction by conventional mechanism not shown which may comprise a separate electrical motor and power transmission means, or may comprise a transmission mechanism connected with the motor 25, it being understood that the regulating wheel 16 is rotated at a speed different from that of the speed of rotation of the grinding wheel 12 so that work placed within the work receiving throat is rotated therebetween during the material removing operation. Mechanism of this type is conventionally known as a centerless grinding machine because fixed centers are not provided for supporting the work 26, such as a stud, bolt or shaft, during material removing operation, the work being supported in such machine by the grinding and regulating wheels and by a longitudinally extending work rest 27. As is well known in the art, such a machine also includes a coolant or cutting fluid circulating system which is supplied to the workpiece 26 during the grinding operation and flows by gravity into a trough or troughs from which it is recirculated by means of a pump 28 in a conventional manner.

In prior art centerless grinding machines it has been conventional to bodily move the regulating wheel towards and away from the grinding wheel to effect feeding of the work, placed within the throat, into engagement with the grinding wheel during the grinding operation and to effect ejection of the work thereafter. It has also been conventional to employ a relatively fixed axis regulating wheel and various mechanical devices to eject the work from the throat after the grinding has been completed. Such a movement of the regulating wheel, or separate ejection devices, are no longer necessary when employing a regulating wheel constructed in accordance with this invention since the feeding during the grinding operation, and the subsequent ejection of the work, are effected solely by rotation of the regulating wheel. That is to say, once the regulating wheel support 14 has been initially adjusted, by

means of the threaded shaft 17 and hand wheel or spider 20, to provide a work receiving throat 24 of a desired dimension, the regulating wheel support and the regulating wheel remain in this position throughout grinding operations.

In accordance with this invention the regulating wheel 16 is no longer of uniform radius throughout its circumference, but instead is provided with three separate and distinct peripheral portions or areas designated 16a, 16b and 16c, respectively. As shown most clearly in Fig. 5, the portion 16a of the regulating wheel is of uniform radius and hence is concentric with the axis of the wheel. The portion 16b of the regulating wheel is eccentric with the greatest radius thereof equal to that of the concentric portion 16a. The portion 16c of the regulating wheel is formed by removing a portion of the periphery of the wheel to provide a recess which is interposed between the eccentric portion having the least radius and one end of the concentric portion. In the preferred embodiment, the portion 16c of the regulating wheel is chordal but it will be readily apparent the recesses of other configurations may be employed.

The initial adjustment of the regulating wheel, by means of the threaded shaft 17, is such that the work receiving throat has a width equal to that of the finished diameter of the work to be ground therein when the concentric portion 16a of the regulating wheel is adjacent the wheel 12. Hence, when the regulating wheel is positioned as shown in Fig. 5, the work receiving throat 24 has a width substantially greater than that of the finished work so that the latter can freely fall out of the work receiving throat as hereinafter described. The eccentric portion 16b of the regulating wheel is so formed that its smallest radius, when adjacent the grinding wheel 12 so as to define the work receiving throat therebetween, provides a throat of greater width than that of the diameter of the work to be ground there-

With a regulating wheel thus constructed, a workpiece 26 is introduced into the work receiving throat 24 when the eccentric portion 16b is adjacent the grinding wheel 12, the workpiece then resting upon the upper edge of a work rest 27, the width of the throat then being such that the workpiece cannot fall from the work rest. As the regulating wheel continues to rotate in a clockwise direction the eccentric portion 16b moves or feeds the workpiece 26 towards the grinding wheel 12 and, since the regulating wheel and grinding wheel are rotating at different speeds, the speed of the regulating wheel preferably being less than that of the grinding wheel, the workpiece 26 is rotated therebetween and material is removed therefrom. The rate of material removal is governed by the speeds of the grinding and regulating wheels and by the eccentricity and the peripheral extent of the eccentric portion 16b which are so selected that the diameter of the workpiece 26 is reduced to its desired final dimension by the time the regulating wheel has rotated to bring the concentric portion 16a into the throat area.

The concentric portion 16a of the regulating wheel then cooperates with the grinding wheel 12 to finish or polish the work and as this concentric portion rotates beyond the throat, the recessed or chordal portion is moved thereinto. This recessed or chordal portion then provides sufficient space for the workpiece 26 to fall freely by gravity from its position upon the top of the

work rest 27. The workpiece 26 is assisted in this movement by the rotation of the grinding wheel 12 and, if desired, this movement may be further assisted by tapering or beveling the upper edge of the work rest 27 as shown in Fig. 6. As soon as the recessed or chordal portion 16c of the regulating wheel has passed beyond the work receiving throat 24, and the eccentric portion 16b is again positioned to form a part of the throat, a new workpiece is introduced into said throat and the operation is repeated. Since the workpiece is fed into engagement with the grinding wheel during the grinding operation, and is removed from the work receiving throat after the grinding is completed, simply by rotation of the regulating wheel itself, the delays interposed by prior mechanisms for performing these functions are removed so that the over-all time for a grinding operation is materially reduced. As the workpieces drop out of the work receiving throat they may be collected in a suitable removable pan placed upon the bed of the machine or may be received within a suitable funnel or chute which directs the workpieces out of the machine and into a suitable receptacle adjacent thereto.

The improved regulating wheel of this invention may be employed with manual feeding or introduction of the work into the work receiving throat, or with conventional feeding mechanism. However, a further aspect of this invention contemplates the provision of an automatic feeding device for sequentially introducing workpieces into the work receiving throat in timed relationship to the rotation of the regulating wheel. For the purpose of disclosing a preferred embodiment of such a feeding mechanism, the apparatus is illustrated and described as adapted for feeding and grinding workpieces in the form of headed cylindrical studs or bolts although it will be understood that suitable conventional changes will permit the feeding mechanism and the regulating wheel of this invention to be employed with workpieces of other types.

As shown in the drawings, the work feeding means comprises a hopper 28 which is here shown as being substantially rectangular with the sides thereof converging towards the bottom. This hopper is preferably formed as two substantially symmetrical halves joined together in spaced relationship, but may be formed as one integral unit with an elongated opening extending substantially medially thereof. Within such an opening or the space provided between the two halves of the hopper, is pivotally mounted a substantially sector-shaped member 29 which is pivoted at one end thereof to spaced ears or flanges 30 provided on the lower side of the hopper adjacent the forward edge thereof. This sector-shaped member 29 may be formed of two plates connected together in spaced relationship so as to provide a slot or groove 31 therebetween, or may be formed of a single integral piece by bending, casting or the like. The sector-shaped member 29 is adapted to be rocked from a position in which its upper edge 32, containing the slot or groove 31, is substantially coextensive with one side and bottom of the hopper to a position as shown in Fig. 4; wherein the said sector extends well above the upper edge of the hopper. This is effected by allowing the lower edge of the sector plate to extend through the bottom of the hopper and by engaging the said lower edge with a roller 33 provided upon the end of a crank arm 34 which is, in turn, rotatably mounted upon a shaft 35. This shaft 35 is supported upon a por-

tion of a bracket or standard 36 which also serves to support the hopper 28.

The shaft 35 is provided with a sprocket wheel 37 which is driven by a motor 38, operating through a gear reduction unit 39 and sprocket wheel 40 to drive a chain 41 passing about the sprocket wheels 37 and 40. Hence, the crank arm 34 is rotated and during each rotation thereof the roller 33 engages the lower edge of the sector 29 and elevates the latter to a position shown in Fig. 4, the sector dropping by gravity to its lowermost position as the roller 33 is moved from under the sector. It will be apparent, therefore, that when the hopper 28 is supplied with headed cylindrical objects such as studs, bolts or the like, they will gravitate to the lower portion of the hopper, and as the sector 29 is periodically raised a portion of these workpieces will be elevated in the manner shown in Fig. 4. That is to say, the shanks of these workpieces will drop into the groove of the sector and the heads thereof will ride upon the edges 32 of the sector. Instead of sprocket wheels 37 and 40 and chain 41, a pulley and belt drive may be employed between the gear reduction unit 39 and shaft 35.

When the workpieces 26 are thus elevated by the sector 29 they will slide along the upper surface or edges 32 of the sector plate and thereby pass out of the hopper adjacent the point of pivot of the sector plate and will move by gravity down an inclined track, generally designated 42, until they are stopped by a rocking feed controlling member 43. This inclined track 42 comprises pairs of spaced side plates, such as 44, which are connected together in predetermined spaced relationship sufficient to allow the shanks of the workpieces 26 to extend therebetween with the heads of the workpieces resting upon the upper edges of the plates. The plates 44 are held in this spaced relationship by means of upstanding brackets or plates 45 attached thereto and extending thereabove, the upper ends of these plates or brackets 45 being connected by threaded shafts or bolts 46 provided with nuts 47 so that the spacing of the plates or members 44 may be adjusted to accommodate workpieces of different diameter. Two of the upstanding plates or brackets 45 are further connected to a side plate 48 which is also connected to a portion of the bracket or support 36 for the hopper 28.

The bracket 36 is provided with two spaced downwardly extending legs 49 and 50. The lower end of the leg 50 is provided with an elongated horizontally extending slot 51, and this leg 50 is supported by a pair of vertically spaced standards or plates 52 between which the leg 50 is received and through which extends a bolt or machine screw 53, the latter also extending through the slot 51 in the leg 50. Legs 49 and 50 of the support 36 are connected by a horizontally extending plate or bar 54, one end of which is attached to the leg 50 and the vertical plates or supports 52 by the bolt or screw 53 and the other end of which is secured to the leg 49 by a bolt or machine screw 55 passing through a slotted opening in the lower end of the leg 49. The upper ends of the vertical supports or plates 52 are provided with horizontal extensions 56 to which the horizontal plate 54 is additionally connected by means of a screw or bolt 57 to hold the parts rigidly and prevent rocking movement. The slots in the arms or legs 49 and 50 of the bracket or support 36 provide for adjustment between the parts for initial assembly. Instead of being a separate member, the plate 54 may, if desired,

be welded or brazed to the arms or legs 49, 50 of support 36. The lower ends of the upstanding plates or brackets 52 are secured to a base plate 58 in any suitable manner.

Adjacent the forward edges of the plates or brackets 52 the plate 53 is provided with an upstanding block or support 59, and spaced forwardly thereof and aligned therewith is a second block or support 60 likewise secured to the base plate 58. The upper ends of these blocks or supports 58 and 60 are bifurcated and receive therebetween a horizontally elongated portion 61 of the work rest or support 27. As shown, the work rest 27 comprises an upstanding flange substantially centrally of the portion 61 and formed integrally therewith, the portion 61 being clamped to the blocks or supports 59 and 60 by bolts or screws 62 and 63. Adjustment of the work rest between the supports or blocks 59 and 60 may be effected by providing elongated slots in the portion 61 through which the bolts or screws 62 and 63 pass, or the work rest portion 27 may be made separable from the horizontal portion 61 and adjustable relative thereto in the well known manner. Also, if desired, the supports 59, 60 need not be made as integral blocks but can be formed as two spaced plates secured together in suitable manner. Instead of securing supporting plates 52 directly at the base plate 58, or in addition to such securing, a plate or plates 64 may be secured between the plates 52 by a bolt or bolts 65 with a portion of the plate or plates 64 extending beyond the plates 52 and welded or otherwise secured to the block or support 59.

A vertically extending plate 66 is bolted to the forward edge of the block or support 60 and extends upwardly adjacent the downwardly curved forward end of the track 42 as shown in Fig. 4. The upper end of this plate or support 66 pivotally mounts the previously mentioned rocking feed controlling member 43 which, as shown in Figs. 3 and 5, is substantially U-shaped with the legs thereof disposed on either side of the forward edge of the track 42. One leg 67 of the rocking member 43 is provided with an inwardly directed pin 68 which is adapted to extend through an opening 69 provided in the adjacent plate or side 44 of the track and when so extending, the pin 68 engages the workpieces 26 moving downwardly along the track 42 to retain the latter in the position shown in the Fig. 4. The other leg 67a of the rocking member 43 has one end of a tension spring 70 attached thereto, the other end of the spring being attached to the track 42 so as to normally rock the member 43 to the position shown in Fig. 3. This leg 67a is likewise provided with an inwardly directed pin 68a adapted to extend through an opening, similar to the opening 69, in the side of the track to engage the workpieces moving therethrough.

The pins 68 and 68a are so spaced and the construction is such that, when the spring 70 urges the member 43 to the position shown in Fig. 3, the pin 68a projects into the track 42 and holds back the workpieces 26 therein. When the member 43 is rocked against the tension of the spring 70 to the position as shown in Fig. 4, the pin 68 is projected into the path of the lowermost workpiece while the pin 68a is withdrawn from the path of the workpieces. When the member 43 is again rocked under the action of the spring 70, the pin 68 is withdrawn from the path of the lowermost workpiece and the pin 68a moves into the track 42 between the lowermost workpiece and the next workpiece. Hence, the lowermost

workpiece is now free to drop into an opening provided in the upper surface of a guide member 71 connected with the vertical support 66. This guide member 71 has its opening substantially

5 aligned with the work rest 27 but with the bottom of the opening in the member 71 spaced vertically above the upper edge of the work rest 27 slightly as indicated in Fig. 4, the workpiece positioned in the member 71 being projected onto 10 the work rest in timed relation with the rotation of the regulating wheel as hereinafter described.

In addition to the side members 44, the track 42 also includes a top strap or member 72 which conforms with the upper edges of the side members 44 but is held in spaced relationship thereabove by suitable brackets 73 connected with side members 44 of the track, the brackets being adjustable to enable the elevation of the member 72 to be adjusted. This member 72 guides the 20 upper ends of the workpieces in their movement along the track 42 and the workpieces 26 are further guided upon their entrance into the track 42 by an eccentrically mounted roller 74 rockably supported upon the hopper 28 at the point of 25 emergence of the workpieces from the groove in the sector 29, the action being such that the roller 74 depresses the heads of the workpieces into engagement with the upper edges of the side members 44 of the track so that the workpieces will feed freely therethrough and will not jam against the cover or strap 72. In order to prevent workpieces from lodging behind and under the sector 29 the rear portion of the slot or opening in the hopper is filled by an adjustable member 75 pivoted to the hopper adjacent the rear edge thereof and held in adjusted position by a screw 76, or the like, passing through an elongated slot in the member 75 and through downwardly projecting ears 77 carried by the hopper.

40 The hopper 28, track 42, work rest 27, and the actuating mechanism for the workpieces, about to be described, are adapted to be mounted as a unit upon a conventional grinding machine by attaching the plate 58 to the bed 11 of the machine in place of the usual work rest provided thereon. This may be effected by a plurality of bolts or other attaching means, the plate 58 being so mounted that the work rest 27 occupies substantially the same position as the conventional work rest provided in such a machine.

50 Pivoted upon the plate 58, at a point spaced forwardly of the support 60, is a rocking actuating arm 78 which may be formed as two spaced members connected together by suitable spacers. Between the ends of the rocking member 78 is pivotally mounted a block 79. This block has a transversely extending bore through which an actuating rod 80 extends, the rod 80 being provided with collars 81 and 82 which are connected to the rod on opposite sides of the pivoted block 79. One end of this rod 80 extends through an opening in the supporting plate 66 and is adapted to contact the head of a workpiece 26 resting in the member 71. The construction is 55 such that as the arm or member 78 is rocked, from the full-line position shown in Fig. 4 to the broken-line position shown therein, the rod 80 strikes the workpiece 26 and forces the latter forwardly into the work receiving throat 24 so that the workpiece rests upon the work rest 27, the movement of the workpiece in this direction being limited by an abutment member 83. This abutment member is substantially aligned with the workpiece when the latter is on the work rest and 70 the abutment member is supported upon the 75 the abutment member is supported upon the

members 52 by passing through a collar 84 connected with the members 52, the position of the abutment 83 being adjustable by sliding the latter through the collar 84 to the desired position and then locking the abutment member within the collar by means of a set screw 85.

The rocking member or arm 78 is moved, as just described, by means of a tension spring 86, one end of which is connected at a point adjacent the top of the rocking member 78, the other end of the spring being connected to a fixed part of the track 42 such as one of the transversely extending bolts or shafts 46. The rocking member 78 is moved in the opposite direction, against the action of the spring 86, by a face cam 87 connected concentrically with the regulating wheel 16, the face of the cam 87 bearing upon a cam roller 88 rotatably supported upon the rocking arm 78, the said roller being positioned so that its axis lies substantially upon a plane passing through a diameter of the regulating wheel. The cam 87 comprises a high or lobe portion 87a and a lower or dwell portion 87b, and the cam is initially so adjusted relative to the regulating wheel that the low portion 87b of the cam allows the rod to move a workpiece 26 into the work receiving throat after the recessed or chordal portion 16c of the regulating wheel has just passed the throat, the high portion 87a of the cam being disposed so that the arm 78 is rocked to its full-line position while a workpiece is being ground within the throat and during the passage of the recessed or chordal portion 16c of the regulating wheel past the throat at which time the workpiece is discharged therefrom.

In addition to operating the rod 80 to feed a new workpiece into the work receiving throat of the grinding machine, the rocking arm 78 also actuates the rocking member 43 to control the movement of the workpieces from the track 42 into the opening in the supporting member 71. This is effected by virtue of the fact that the arm 78 strikes the rocking member 43 when the arm 78 is in its broken-line position as shown in Fig. 4. This rocks the member 43 to move the pin 68 into the path of the lowermost workpiece and to withdraw the pin 68a, as previously described, while the rod 80 is projecting a workpiece into the work receiving throat. When the cam 87 moves the member 78 to its full-line position as shown in Fig. 4, the member 43 is again rocked to the position as shown in Fig. 3, by the spring 70, thus allowing a single pin to drop from the track 42 into the opening in the member 71 in position to be actuated by the rod 80 when the latter is again moved forwardly under the action of the spring 86 as permitted by the low portion 87b of the cam. Hence, workpieces are sequentially fed in a longitudinal direction into the work receiving throat where they are initially supported by the work rest 27 and are then fed into grinding engagement with the grinding wheel 12 by the regulating wheel 16. The recessed or chordal portion 16c of the latter permits the workpieces to drop from the work receiving throat when the grinding operation is complete, the cam carried by the wheel operating the feeding mechanism to position a new workpiece within the work receiving throat when the grinding operation on the preceding workpiece is complete and the regulating wheel has rotated to bring the eccentric portion adjacent the work rest.

It will be observed that, in the illustrated embodiment, the rod 80 does not hold the work-

pieces in the work receiving throat but simply feeds them therein and is retracted from engagement with the workpieces during the grinding operation. Where the workpieces are headed 5 studs, as shown, it is not absolutely necessary that an abutment member 83 be provided since the parts may be so positioned that the head of the workpiece engages the edge of the work rest to limit its longitudinal movement into the work receiving throat. However, the provision of an abutment member 83 is advantageous because it insures that workpieces cannot be projected too far within the work receiving throat as might occur in certain instances where the head of the workpiece did not properly engage the work rest.

If it be desired to terminate feeding of workpieces this can be readily accomplished in the illustrated machine without stopping the motor 38 by simply dropping a latch or abutment member 88 into the path of an adjustable collar 89 provided upon the threaded outer end of the shaft 80, this latch or abutment member being pivotally mounted upon a vertical support 99 attached to the base plate 58. By so dropping the

25 latch or abutment member 88, the latter engages the collar 89 preventing the spring 86 from moving the rod 80 to feed a new workpiece into the work receiving throat. Feeding operation may be resumed by simply lifting the latch or abutment member 88 from engagement with the collar 89. Operation of the entire machine may be readily terminated by the usual electrical circuit and control box since the motor 25 for the

30 regulating wheel 12, the motor for the regulating wheel, if the latter has a separate motor, and the motor 38 for the feeding mechanism are connected in a suitable circuit controlled by start and stop buttons 91 and 92 respectively, mounted at a convenient point upon the base of the machine. If desired, a separate switch may be provided for the motor 38 of the feeding mechanism in order that feeding of workpieces from the hopper may be terminated without stopping the entire machine.

45 The grinding machine is illustrated in Figs. 1 to 6 as provided with a regulating wheel truing or dressing attachment 23 of conventional design. It will be readily apparent, however, that the entire periphery of the novel regulating wheel of this invention cannot be dressed by such an attachment. However, the concentric portion 16a of the regulating wheel can be so dressed or trued and since it is this portion which controls the finished diameter of the work, it is the portion which would normally require the most frequent truing or dressing. The truing device 23 will cooperate with this portion of the wheel in the conventional manner which is well understood and, hence, need not be described in detail.

50 55 60 65 70 75 80 85 90 95 100

If other portions of the wheel should require dressing or truing it is ordinarily necessary, when a conventional truing or dressing device is employed, to remove the wheel from the machine to effect such operations. It should be observed, however, that frequent dressing of the portions 16b and 16c of the regulating wheel will not be necessary and satisfactory operation is obtained over relatively long periods of use by simply dressing the portion 16a and adjusting the width

of the work receiving throat by means of a hand wheel or spider 20, after the said dressing has been accomplished, to maintain the finished dimension of the workpieces at the desired value.

In order to obviate the necessity for removing the regulating wheel 16 from the machine to

11

effect dressing or truing of the eccentric portion 16b, the conventional dressing means 23 may be replaced by the novel truing or dressing means 23' illustrated in Figs. 7 and 8 of the drawings. This means comprises the usual housing 95 which is movably mounted upon dovetail ways 96 provided upon the slotted forward portion of the regulating wheel housing 14, the housing 95 being movable transversely of the regulating wheel by the conventional handwheel 97 and screw 98 or by hydraulic means, as is well known in the art. A sleeve 99 is slidably mounted in a substantially vertical bore in the housing 95, and a diamond holding bar 100 is slidably disposed within the sleeve 99. The lower end of the diamond holder bar is provided with dovetail ways for adjustably mounting the diamond support 101 with the diamond 102 projecting from the lower surface of the support for engagement with the regulating wheel 16 when this wheel is to be dressed or trued.

The upper end of the diamond holder bar 100 is provided with a threaded bore in its upper end within which is screwed the lower end of an adjusting screw 103. The upper end of this screw is provided with a graduated sleeve 104 having a handle 105 extending transversely therethrough and the screw 103 is rotatably mounted, but held against longitudinal displacement, by a collar 106 mounted in the upper end of the sleeve 99. The diamond holder bar 100 is held from rotation by means of a longitudinal extending groove and a cooperating gib 107. The construction is such that turning the handle 105 and the graduated sleeve 104, causes the diamond holder bar to move longitudinally relative to the sleeve 99 thereby adjusting the diamond 102 with respect to the regulating wheel 16.

Mounted upon the regulating wheel spindle to rotate therewith is a cam 108 which has a concentric portion 108a, an eccentric portion 108b and an irregular curved portion 108c. The lower end of the sleeve 99 is provided with a transversely extending bracket member 109 provided with an elongated cam follower 110 which rides upon the cam 108. The cam follower is urged into engagement with the cam by a compression spring 111 acting between the housing 95 and a bracket 112 fixed to the sleeve 99 and having a portion projecting through an opening in the housing 95. The bracket 112 is also provided with a clamping means including a screw 113 which extends through an opening in the housing and is adapted to clamp the sleeve 99 and the diamond holding bar 100 together. The construction is such that, as the regulating wheel 16 and cam 108 are rotated, the cam follower 110 causes the sleeve 99 and the diamond holder bar to be moved so that the diamond 102 accurately trues or dresses the eccentric and concentric portions of the regulating wheel to the proper curvature, the portion 108c of the cam moving the diamond away from the regulating wheel while the recessed portion of the latter is passing under the former. This prevents injury to the corners of the regulating wheel formed by intersection of the chordal portion of the wheel with the concentric and eccentric portions thereof, while permitting accurate dressing of the concentric and eccentric portions immediately adjacent the corners. Since the recessed portion of the regulating wheel simply controls the discharge of a workpiece after being ground, it does not need to be dressed.

During the time when the diamond 102 is con-

12

tacting the regulating wheel, under control of the cam 108, the housing 95, and hence the diamond, are traversed with respect to the regulating wheel by means of the handwheel 97 and screw 98, or by conventional hydraulically operated means, so that the entire width of the regulating wheel is dressed or trued. It will be observed that the cam follower 110 has a wide face so that it will remain in contact with the 5 cam while the diamond is being traversed over the entire width of the regulating wheel. Preferably, the width of the cam follower is sufficient so that the diamond may be moved beyond the regulator wheel after the dressing or truing of the latter is completed.

The diamond may also be disengaged from the regulating wheel by operation of the handle 114 which is pivoted to the housing 95 and operates in the conventional manner to elevate or 10 lower the sleeve 99. The housing 95 is also provided with a clamping means including a screw 115 which cooperates with the sleeve 99 to clamp the latter to the housing 95 to hold the diamond from engagement with the regulating wheel after 15 the handle 114 has been operated to raise the diamond.

While the regulating wheel is here shown as having its axis substantially parallel with the axis of the grinding wheel 12, it will be apparent 20 that the axes of these wheels may be disposed at a slight angle with respect to each other, if desired, for grinding tapered workpieces as is well known in the art and this will not interfere with the operation of the device.

25 It is believed that the mechanism of this invention will now be readily apparent from the above described embodiments. Briefly summarized, the operation is as follows:

Workpieces 26 to be ground are supplied to the 30 hopper 28 and the start button 91 is actuated. Actuation of button 91 starts the motor or motors for rotating the grinding wheel and regulating wheel. If the feeding motor 38 is wired for control by the buttons 91 and 92, it also starts when 35 the button 91 is actuated. If a separate switch is provided for the feeding motor 38 this switch is preferably actuated after the actuation of the button 91. As the motor 38 rotates it drives the chain or belt 41, which in turn rotates the crank 45 arm 34, so that the roller 33 on the latter rocks the sector member 29 within the hopper 28. Each time the sector member 29 is raised, to the position as indicated in Fig. 4, certain of the workpieces within the hopper will be lifted thereby 50 since the converging configuration of the hopper and the stirring action of the sector member aligns the workpieces so that the shanks of at least some of the workpieces drop into the groove 31 in the sector member each time it is actuated. 55 The workpieces which are so positioned within the groove 31, during each rocking motion of the sector member 29, move by gravity from the latter when it is elevated and passed into the track 42, the eccentrically mounted weight member 74 insuring that the heads of all of the workpieces are suitably positioned as they move into the track.

As the workpieces move downwardly through the track 42 under the influence of gravity, the 60 lowermost workpiece engages the pin 68a until the regulating wheel has rotated sufficiently to cause the low part 87b of the cam 87 to come adjacent the roller 88. This operation of the cam enables the arm or member 78 to rock to 65 its broken-line position as shown in Fig. 4 under

influence of the spring 86 and when so rocked, the arm or member 78 strikes the rocking member 43 moving the pin 68a from engagement with the lowermost workpiece and bringing the pin 68 into the path thereof. When the high point of the cam 87a again moves the rocking arm or member 78 to its rearmost position as shown in Fig. 4, the member 43 rocks under the influence of the spring 70 thereby moving the pin 68 from engagement with the lowermost workpiece and bringing the pin 68a into the path of the next succeeding workpiece.

The lowermost workpiece thus freed, drops into the opening of the support member 71 and hence, when the rocking member 78 again moves to its broken-line position as shown in Fig. 4, the rod 80 engages the workpiece so positioned upon the member 71, forcing the latter into the work receiving throat between the grinding and regulating wheels with the workpiece resting upon the work rest 27. The device is so timed that when the workpiece is thus projected or positioned, the eccentric portion of the regulating wheel will be adjacent the work receiving throat so that the said workpiece cannot drop therefrom.

As the regulating wheel continues to rotate, the eccentric portion 16b thereof feeds the workpiece against the grinding wheel and the joint action of the grinding and regulating wheels rotates the workpiece and removes material therefrom, this action continuing until the concentric portion 16a of the regulating wheel is adjacent the work receiving throat. At this time no further feeding of the work against the grinding wheel occurs but the continued action of the regulating and grinding wheels is effective to finish or polish the workpiece to the desired final dimensions. Continued rotation of the regulating wheel then brings the recessed or chordal portion 16c adjacent the work receiving throat and the workpiece 26 then drops from its position on the work rest 27, being assisted in this action by the rotation of the grinding wheel. After the recessed or chordal portion has passed the work receiving throat and the eccentric portion 16b is again adjacent thereto, the cam 87 will have been moved to a position allowing the rocking arm or member 78 to again feed a new workpiece into the work receiving throat, it being understood that the high point in the cam 87 had previously withdrawn the rod 80 from engagement with the workpiece during the grinding operation upon the workpiece and during this backward movement of the rocking member 78, the member 43 was actuated by the spring 70 to drop another workpiece upon the supporting member 71 into position to be fed into the work receiving throat by the rod 80. Hence workpieces are sequentially fed into the work receiving throat where the regulating wheel feeds them against the grinding wheel and the two wheels cooperate to grind the work to a finished diameter, the regulating wheel's continued rotation thereafter causing discharge or rejection of the finished workpiece. This operation continues so long as workpieces are present in the hopper 28 or the track 42.

While the present preferred embodiment of the invention and a modification thereof have been described and illustrated in considerable detail it will be readily apparent that numerous variations and modifications may be made therein without departing from the spirit of the invention. Thus, the concentric portion of the regulating wheel need not be provided in certain in-

stances, the periphery of this wheel then consisting only of recessed and eccentric portions. Moreover, while the invention has been disclosed as comprising a novel regulating wheel, feeding device, and a truing device it will be readily apparent that any of these may be used without the other if so desired, although the maximum efficiency of the machine is achieved when all are used together. Other variations and adaptations of the mechanism will be readily apparent to those skilled in the art and therefore the invention is not to be considered as limited to the exact details herein illustrated and described but only as required by the spirit and scope of the appended claims.

Having thus described the invention, we claim:

1. A centerless grinder comprising opposed rotatable grinding and regulating wheels mounted in spaced relationship to form a workpiece receiving throat therebetween, the said regulating wheel having a segment of its periphery removed to provide a recessed portion and the remainder of its periphery including an eccentric portion with the greatest radius thereof being such that when disposed in the line passing through the centers of the grinding and regulating wheels to form one side of said workpiece receiving throat the width of the latter is substantially equal to the desired final diameter of the workpieces, a supply hopper for receiving elongated workpieces with their axes extending in diverse and non-ordered directions, an inclined track having its upper end adjacent said hopper and its lower end adjacent said throat, means communicating with the upper end of said track and movable through said hopper to periodically remove workpieces from said hopper in a predetermined ordered arrangement and to introduce said removed workpieces onto the upper end of said inclined track in the ordered arrangement, a stationary support aligned with said throat and positioned for receiving a workpiece from the lower end of said track, and means operated in timed relationship with said regulating wheel to control sequential delivery of said workpieces from said track onto said support and to axially move each workpiece from said support into said throat whereupon the eccentric portion of the regulating wheel progressively feeds the workpiece in said throat towards the grinding wheel for effecting material removal and the recessed portion of the regulating wheel allows the workpiece to drop by gravity from its position within the said throat after the grinding is completed.
2. A centerless grinding machine comprising opposed rotatable grinding and regulating wheels mounted in spaced relationship to form a workpiece receiving throat therebetween, a supply hopper for receiving elongated workpieces with their axes extending in diverse and non-ordered directions, an inclined track having its upper end adjacent said hopper and its lower end adjacent said throat, means communicating with the upper end of said track and movable through said hopper to periodically remove workpieces from said hopper in a predetermined ordered arrangement and to introduce the removed workpieces into the upper end of an inclined track in ordered arrangement, means adjacent the lower end of said track operable to control one-at-a-time delivery of workpieces therefrom, means to move a delivered workpiece axially into said throat, and means operated in timed relationship with the rotation of said regulating

wheel to effect sequential operation of said control means and said workpiece moving means.

3. A workpiece feeding mechanism for a centerless grinding machine having opposed rotatable grinding and regulating wheels mounted in spaced relationship to form a workpiece receiving throat therebetween, the said mechanism comprising a supply hopper for receiving elongated workpieces with their axes extending in non-ordered directions, an inclined track having its upper end in communication with said hopper and its lower end disposed adjacent said throat, the said track being adapted to convey workpieces in single file order from the said hopper, means for removing workpieces from said hopper in single file ordered arrangement and for introducing them into the upper end of said inclined track, a stationary workpiece support spaced below the lower end of said track in alignment with the said throat, means adjacent the lower end of said inclined track adapted to be sequentially operated to control delivery of the workpieces one-at-a-time from said track to said support, reciprocating means for axially moving a workpiece from said support into said throat, and a single rockably mounted member cooperating with reciprocating means and said means controlling delivery of workpieces to said support to effect sequential operation thereof.

4. A workpiece feeding mechanism for a centerless grinding machine having opposed rotatable grinding and regulating wheels mounted in spaced relationship to form a workpiece receiving throat therebetween, the said mechanism comprising a supply hopper for receiving elongated workpieces with their axes extending in non-ordered directions, an inclined track having its upper end adjacent said hopper and its lower end disposed adjacent said throat, the said track being adapted to convey workpieces in single file order from the said hopper, means in communication with the upper end of said track and movable through said hopper to periodically remove workpieces from said hopper in single file ordered arrangement and to introduce the said removed workpieces into the upper end of said inclined track in ordered arrangement, a stationary workpiece support spaced below the lower end of said track in alignment with the said throat, a member movable transversely of said track adjacent the lower end thereof to control delivery of the

workpieces from said track to said support, a member mounted for reciprocation over said support and adapted to engage a workpiece thereon and move the latter axially into said throat, and means for sequentially operating said movable member and said reciprocable member.

5. A workpiece feeding mechanism for a centerless grinding machine having opposed rotatable grinding and regulating wheels mounted in spaced relationship to form a workpiece receiving throat therebetween, the said mechanism comprising a supply hopper for receiving elongated workpieces with their axes extending in non-ordered directions, an inclined track having its upper end in communication with said hopper and its lower end disposed adjacent said throat, the said track being adapted to convey workpieces in single file order from the said hopper, means for removing workpieces from said hopper in single file ordered arrangement and for introducing them into the upper end of said inclined track, a stationary workpiece support spaced below the lower end of said track in alignment with the said throat, a member movable transversely of said track adjacent the lower end thereof to control delivery of the workpieces from said track to said support, a member mounted for reciprocation over said support and adapted to engage a workpiece thereon and move the latter axially into said throat, and a single rockable member cooperating with said movable member and said reciprocable member to effect sequential operation thereof.
